UNITED STATES PATENT OFFICE.

SAMUEL C. ARTHUR, OF WAUKEGAN, ILLINOIS, ASSIGNOR TO CYCLONE FENCE COMPANY, OF WAUKEGAN, ILLINOIS, A CORPORATION OF ILLINOIS.

NON-CLIMBABLE FENCE.

1,237,601.

Specification of Letters Patent. Patented Aug. 21, 1917.

Application filed December 14, 1915. Serial No. 66,706.

To all whom it may concern:

Be it known that I, SAMUEL C. ARTHUR, a citizen of the United States, and a resident of Waukegan, county of Lake and State of Illinois, have invented certain new and useful Improvements in Non-Climbable Fences, of which the following is a specification.

My invention relates to improvements in nonclimbable fences, and has for its object 10 the provision of a simple and efficient construction of this character which is capable of economical production.

The invention consists in the combinations and arrangements of parts hereinafter described and claimed.

The invention will be best understood by reference to the accompanying drawings forming a part of this specification, and in which,

20 Figure 1 is a top plan view of a fence guard member,

Fig. 2, a side view of the same shown partially in section,

25 Fig. 3, an enlarged section taken on line 3—3 of Fig. 2,

Fig. 4, a section taken on line 4—4 of Fig. 2,

30 Fig. 4^a, a detail section illustrating means for effecting a tight connection between a fence guard member and a fence post,

Fig. 5, a top plan view of a modified form of construction,

Fig. 6, a side view of the same shown partially in section,

35 Fig. 7, an enlarged section taken on line 7—7 of Fig. 6, and

Fig. 8, an enlarged view taken on line 8—8 of Fig. 6.

The preferred form of construction, as 40 illustrated in the drawings, comprises a fence guard member 9 made in channel form and secured in position by means of a depending stem 10 adapted to fit within the top of a tubular fence post 11, said guard member being arranged in inclined position 45 with its open side down, as shown. As indicated in Fig. 4, the stem 10 and guard member 9 are provided with a slot 10' at one side for the reception of a wedge 11', this 50 construction being provided to effect a tight connection in case the fence post 11 is somewhat larger than the stem 10, as indicated. The upper or closed side of the guard member 9 is provided with a plurality 55 of notches 12 adapted to receive ordinary

barbed wire fence strands 13. A locking member 14 consisting of a suitable piece of wire is arranged to be inserted between the fence strands or wires 13 and the closed side of channel member 9, said locking member 60 14 being provided at its upper end with a hook 15 arranged to engage over the uppermost wire 13 upon insertion of said locking member. After insertion, the hook 15 is bent into closed position, as shown in Fig. 2, 65 to secure the same against removal. A vertically elongated opening 16 is provided at the base of guard member 9 immediately above post 11, the sides of said opening being beveled, as shown, to facilitate the 70 positioning of the top rail of a fence therein in inclined position, as is necessary where the fence is built over hilly ground.

In use, the fence posts 11 are set in the usual manner and guard members 9 secured 75 in the tops thereof projecting laterally from the line of the fence. Then the fence wires or strands 13 are stretched between the guard members 9 and placed in the notches 12. Then locking wires 14 are inserted in 80 the channel members 9 between the wire strands 13 and the upper or closed side of guard member 9, the hook 15 on each locking member 14 being bent around the uppermost wire 13, as shown.

85 In the modified form of construction, two guard members 17 are provided arranged at an angle to each other and supported on a suitable bracket 17' adapted to be positioned on the top of a fence post with the guard 90 members projecting laterally from each side of the fence line. These guard members are also in the form of inclined open channels having their open sides down and are provided with notches 18 in their upper sides to receive the fence wires or strands 19. A vertical notch 20 is also provided at the apex of the guard members 17 for the reception of the topmost wire 21 of the fence. A locking member 22 consisting of a wire 100 having a hook 23 at its upper end is inserted in each of the guard members 17 as indicated with the hook 23 engaging over the wire 21, notches 24 being provided in the closed sides of the guard members to permit of the insertion of said locking members. The fence is assembled substantially as before, but the hooks 23 are not bent around the uppermost wire 21 since this wire is inaccessible. This construction furnishes 110

a fence which cannot be climbed from either side.

While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. The combination with a fence post, of a fence guard secured to the top thereof in an inclined position, said guard consisting of an inclined channel member arranged with its open side down and provided with notches in its closed side to receive fence

wires; and a locking member inserted in said channel between said wires and said notches, substantially as described.

2. The combination with a fence post, of a fence guard secured to the top thereof in an inclined position, said guard consisting of a channel member arranged with its open side down and provided with notches in its closed side to receive fence wires; and a wire inserted in said channel member between said fence wires and said notches, the upper end of said inserted wire being provided with a hook engaging the uppermost of said fence wires, substantially as described.

In testimony whereof I have signed my name to this specification in the presence of two subscribing witnesses.

SAMUEL C. ARTHUR.
